UNITED STATES PATENT OFFICE.

SHERWOOD HINDS, OF ST. LOUIS, MISSOURI, ASSIGNOR TO ST. LOUIS PUMP & EQUIPMENT COMPANY, OF ST. LOUIS, MISSOURI, A CORPORATION OF MISSOURI.

ROTARY PUMP.

Application filed May 26, 1924, Serial No. 715,849. Renewed February 11, 1928.

This invention relates to pumps, and with regard to certain more specific features, to positive-acting rotary pumps of the ungeared type, suitable for pumping either liquids or 5 gases.

Among the several objects of the invention may be noted the provision of low relative velocities between points in contact at the sealing juncture between the intake and discharge sides of the pump, and the provision of means for decreasing to a minimum objectionable clearance volume. Other objects will be in part obvious and in part pointed out hereinafter.

15 The invention accordingly comprises the features of construction, elements and combinations of elements, and arrangements of parts, which are exemplified in the construction hereinafter described and the scope of 20 the application of which will be indicated in the following claims.

In the accompanying drawings, in which is shown one of various possible embodiments of this invention,

25 Fig. 1 is a side elevation of the pump with one side plate removed, being substantially a vertical transverse section on the line 1—1 of Fig. 7;

30 Fig. 2 is a similar view, showing other positions of the movable parts;

Fig. 3 is a vertical section on the line 3—3 of Fig. 7, showing the parts at the beginning of discharge and intake operations;

Fig. 4 is a horizontal section on the line 35 4—4 of Fig. 3;

Fig. 5 is a perspective of an oscillating abutment;

Fig. 6 is a perspective of an oscillating discharge check valve; and

40 Fig. 7 is a horizontal section on the line 7—7 of Fig. 1, on a reduced scale.

Similar reference characters indicate corresponding parts throughout the several views of the drawings.

45 Referring now more particularly to Figs. 1—4 of the drawings, there is shown a casing 1 comprising six chambers disposed as follows: an intake chamber or passage 3, forwardly located and connected by means of intake 50 ports 5 and 7 to two pumping chambers 9 and 11 laterally and downwardly disposed; these pumping chambers 9 and 11 are in turn normally connected by means of discharge passages 10 and 12 to two discharge chambers 13 and 15 located above said pumping chambers.

The discharge chambers 13 and 15 have a common rearward outlet 17. The discharge chambers 13 and 15 are not entirely separated from one another, because the parting wall 21 (Figs. 3 and 4), separating the pumping chambers 9 and 11, does not extend to the top of the pump. The suction inlet 19 to the pump is located forwardly.

The two pumping chambers 9 and 11 and their pumping linkages, to be described later, are made in duplicate, said pumping linkages, however, being mounted oppositely to one another. The pumping cycle is 360 degrees. This arrangement decreases vibration.

The number of pumping chambers can be 70 increased by properly phasing their pumping linkages. As the operations of one chamber are typical of all, only the chamber 9 and its linkage will be described in detail.

The pumping chamber 9 comprises an incomplete cylinder 23 bored from the side of the casing 1. One cylinder end is formed by the parting wall 21 and the other by a cover plate such as the plate 22 in Fig. 4. The wall 21 and cover plate are both machined flat on their inner side. A drive shaft 27 is mounted horizontally along the center line of the cylinder 23 and passes through the parting wall 21 and the cover plate within suitable bearings. Within the chamber 9, the drive shaft 27 carries upon it an eccentric 29. The distance from the furthermost edge of this eccentric 29 to the center-line of the drive shaft 27 is less than the radius of the cylinder by an amount slightly greater than the thickness 80 of the eccentric strap 31 placed around the eccentric 29.

Within the upper left-hand quadrant of the eccentric strap 31 is laterally imbedded and secured a key 33, the key 33 also being imbedded in and secured to a laterally disposed shaft 35 oscillating in the sealing block 39 of the oscillating abutment 37. The eccentric strap 31, the key 33 and the oscillating shaft 35 form a rigid oscillating connecting link 36 between the eccentric 29 and the oscillating abutment 37. The oscillating abutment 37 (Fig. 5) comprises an arm 43 and the sealing block 39 in which oscillates the link 36 on the shaft 35, (Fig. 1—3). The sealing block 39 and link 36 serve to separate the discharge from the intake side of the pump. The sealing block 39 oscillates substantially upwardly and downwardly about the laterally disposed rock-shaft 41, and the 90 100 110

block has its forward surface 45 machined cylindrically with the center-line of the rock-shaft as center. Said surface 45 engages a similarly machined surface 37 on the wall 49 which divides the valve chambers 13 and 15 from the intake chamber 3. The abutment 37 is of bronze and the pump casing is of cast iron. This makes the originally tight seal between the engaging surfaces 45 and 47 of a permanent character. Furthermore, the pumped fluid forms the actual seal between the surfaces 45 and 47. In the case of a liquid this is due to capillary action and in the case of gases to stagnation.

15 The discharge valve 51 (Fig. 6) is rotatably mounted on the rock-shaft 41. This valve comprises two arms 53 in which are bored holes 55 for mounting on the rock-shaft 41 (Fig. 6). The two arms are joined at their forward ends by the substantially vertical valve gate 57, whose inner cylindrical surface 59 is machined to conform to the adjacent surface 61 of the pump housing. These surfaces 59 and 61 are machined with the rock-shaft center-line as center. They are sealed in the same manner as the above described surfaces 45 and 47 of the sealing block and forward wall. The valve is of bronze. The lower surface 63 of the valve gate is so machined that it is cylindrical with respect to the center line of the drive shaft as center when the gate is in the position shown in Fig. 3. This surface 63 thus forms part of the incomplete cylinder 23 when the valve is raised to its fullest extent (Figs. 1 and 3). The gate 57 is made wider than the valve as a whole, in order that it may be economically machined for end-fitting between the wall 21 and the end plate. This construction, furthermore, results in 40 relatively little frictional resistance of the valve for a given tightness of joint.

15 The exhaust valve 51 as a whole straddles the arm 43 of the abutment 37 on the rock-shaft 41. On one of its arms 53 is disposed the bell-crank 65, said bell-crank 65 having formed at upper remote end a lug 67. When the valve rises, this lug 67 comes against an adjustable stop 69 screwed into the pump case 1. In the present embodiment the stop 69 50 comprises an adjustable bolt and a locking nut.

Formed on the under side of one of the arms 53 is the lug stop 71 (Figs. 1-3 and 6) which serves to limit the downward valve travel by striking the wall of the cylinder 23.

It should be here noted that all elements of the oscillating link 36, comprising the eccentric strap 31, key 33 and oscillating shaft 35, as well as the sealing block 39, are all machined as regards lateral dimensions to fit snugly between the machined wall 21 and the machined cover plate, there being provided no rings or other mechanical device to effect a seal. The liquid or gas being pumped acts as an effective seal. This construction makes pack-

ing glands around the drive shaft 27 unnecessary, as no fluid reaches the shaft. Likewise no fluid can reach the surface between the eccentric 29 and its strap 31 to cut a lubricant there. Nor can the lubricant leak out. Consequently at the surface of highest rubbing-speed, lubrication can be carried on under favorable conditions. All other rubbing surfaces on the pump are in contact with the pumped fluid but have low relative velocities. This is particularly advantageous where thin, volatile fluids are being pumped. The eccentric strap 31 is made of cast-iron or bronze, while its eccentric is made of a dissimilar metal in order to insure long wear at the bearing surface.

175 Referring now to Figs. 1-3, the operation of the pump in one chamber is as follows:

The eccentric strap 31 is given, by means of the eccentric 29, an oscillatory motion with 85 and about the oscillating shaft 35 and coincidentally swings eccentrically about the drive shaft 27. The eccentricity of the eccentric disc 29 is such that under normal conditions a point 73 (Figs. 1-3), on the outermost edge of the eccentric strap, is in grazing contact with the eccentric wall of the partial cylinder 23, while an oppositely located point on the strap is some distance from the cylinder wall. This arrangement of parts results in a somewhat crescent-shaped forcing chamber being formed and likewise a suction chamber, each of which revolves counter-clockwise about the cylinder wall, the eccentric strap being the forcing member of the pump (Fig. 1).

A seal is formed at the grazing point 73 by the pumped fluid, such seal being promoted by the fact that the point 73 and the wall have almost a perfect rolling contact, when they do make contact, there being only a slight relative velocity. Should contact take place between the strap 31 and cylinder wall 23 due to wear of the eccentric the low relative velocities will decrease the wear.

105 The suction chamber becomes a forcing chamber as the grazing point 73 passes the lower lip 75 of the intake passage 5 (Figs. 2 and 3). In Fig. 2 the suction chamber has just become a forcing chamber, the charge having been taken in and being about to be compressed. The head pressure in the exhaust chamber 13 holds the discharge valve 51 down, its horizontal projected area being great enough to cause a downward seating force.

110 In the pump position referred to (Fig. 2), the charge has been cut off from the suction side because the grazing point 73 has passed the lip 75.

125 As the eccentric moves counter-clockwise the condition shown in Fig. 1 is met with wherein the crescent-shaped forcing chamber (rearwardly disposed) is becoming smaller as it revolves, thereby compressing and forcing its contents out through the discharge 130

passage 10, to the discharge chamber 13, the fluid having been compressed to such a degree that it has opened the discharge valve to its maximum; that is, the discharge valve lug 5 67 has touched its stop 69.

The discharge valve 51 under no conditions can cut off the flow to the discharge when the pump is near that part of its cycle shown in Fig. 1, because as the stop 71 prevents the gate 10 57 from touching the eccentric while the pump is compressing.

As soon as the grazing point 73 has passed the forward edge of the lower surface 63 on the discharge valve 51 and up to the time said 15 point passes lip 75, the gate 57 on the valve 51 is pressed down by the discharge head pressure, the suction chamber being under lower pressure. During this period of the cycle the gate 57 rests on the eccentric strap 31 (Fig. 20 2), because as the stop 67 is not effective until the eccentric 29 drops the strap 31 to a position corresponding to the passage of the grazing point 73 over lip 75. The result of this is that during the time the compressing chamber 25 is connected with the discharge chamber, the valve is always open and during the time the suction chamber could be connected to the discharge chamber 13 as far as contiguity is concerned, the valve is closed, that is, pressed 30 down and in contact with the eccentric strap, cutting off the return of compressed fluid, and continues so until the suction chamber becomes a pressure chamber.

By reason of the above described means the 35 pump in emptying its compression chamber, in effect, does away with the chamber entirely and the suction event is carried on by a different chamber which in turn becomes a compression chamber. This construction reduces 40 or eliminates re-expansion (in the case of gaseous fluid) of the volume ordinarily trapped in the clearance space of the ordinary reciprocating pump. The present device therefore has more capacity for a given size.

Fig. 2 shows a charge of fluid just as it has 45 been cut off from the suction side of the pump but not yet compressed, the discharge valve being pressed to its lowermost position by discharge head pressure, Fig. 2, shows the 50 last point of contact between the eccentric strap 31 and the gate 57.

Fig. 3 shows the arrangement an instant later when the charge has been slightly compressed, the eccentric strap having dropped 55 away from the gate 59 of the discharge valve 51, permitting compressed fluid to flow to the discharge and incidentally allowing said fluid to open further the discharge valve gate by means of a wedging action.

Fig. 1 shows the suction chamber forming, and drawing in a charge while the compression chamber empties itself.

The valve action in this pump is controlled by the pressures involved and without cams 60 or other linkage, and no intake valve is re-

quired. The pump is thus compact, and inexpensive to construct.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. A pump comprising a casing having 80 intake and discharge chambers and a cylinder, a drive shaft in the cylinder, an eccentric on the drive shaft, a strap on the eccentric, the strap having a close fit within the cylinder whereby rotation of the shaft causes the strap to force fluid ahead of the strap and to draw fluid in behind the strap, the cylinder having an opening, a rocker mounted in the casing, a link connecting the rocker and strap and serving as a seal between the intake and discharge chambers, and an oscillating check valve mounted coaxially with the rocker and forced against the strap by pressure of fluid in the discharge chamber when the grazing point of strap against cylinder reaches the 90 incomplete portion of the cylinder.

2. A pump comprising a casing having intake and discharge chambers and a cylinder, a drive shaft in the cylinder, an eccentric on the drive shaft, a strap on the eccentric, the strap having a close fit within the cylinder whereby rotation of the shaft causes the strap to force fluid ahead of the strap and to draw fluid in behind the strap, the cylinder having an opening, a rocker mounted in the casing, a link connecting the rocker and strap and serving as a seal between the intake and discharge chambers, and a check valve forced 100 against the strap by pressure of fluid in the discharge chamber when the grazing point of strap against cylinder reaches the incomplete portion of the cylinder, the valve fitting the contour of the strap as the grazing point reaches said incomplete portion of the cylinder.

3. A pump comprising a casing having intake and discharge chambers and a cylinder, a drive shaft in the cylinder, an eccentric on the drive shaft, a strap on the eccentric, the strap having a close fit within the cylinder 110 whereby rotation of the shaft causes the strap to force fluid ahead of the strap and to draw fluid in behind the strap, the cylinder having an opening, a seal between intake and discharge chambers, and a check valve forced 120 against the strap by pressure of fluid in the discharge chamber when the grazing point of strap against cylinder reaches the incomplete portion of the cylinder, the valve having its edge nearest the cylinder away from 130

the strap as the grazing point reaches the cylinder again, whereby the next fluid forced against the underside of the valve wedges the valve away from the strap.

- 5 4. A pump comprising a casing having intake and discharge chambers and a cylinder, a drive shaft in the cylinder, an eccentric on the drive shaft, a strap on the eccentric, the strap having a close fit within the cylinder 10 whereby rotation of the shaft causes the strap to force fluid ahead of the strap and to draw fluid in behind the strap, the cylinder having an opening, a rocker mounted in the casing, a link connecting the rocker and strap and serving as a seal between the intake and discharge chambers, and a check valve forced against the strap by pressure of fluid in the discharge chamber when the grazing point of strap against cylinder 15 reaches the incomplete portion of the cylinder the valve fitting the contour of the strap as the grazing point reaches said incomplete portion of the cylinder and having its edge nearest the cylinder away from the strap as the grazing point reaches the cylinder again, whereby the next fluid forced against the underside of the valve wedges the valve away from the strap, and a stop limiting the travel of the valve in a direction toward the strap.
- 20 5. A pump comprising a casing having intake and discharge chambers and a cylinder, a drive shaft in the cylinder, an eccentric on the drive shaft, a strap on the eccentric, the strap having a close fit within the cylinder 25 whereby rotation of the shaft causes the strap to force fluid ahead of the strap and to draw fluid in behind the strap, the cylinder having an opening, a rocker mounted in the casing a link connecting the rocker and strap and serving as a seal between the intake and discharge 30 chambers, a check valve forced against the strap by pressure of fluid in the discharge chamber when the grazing point of strap against cylinder reaches the incomplete portion of the cylinder, the valve fitting the contour of the strap as the grazing point reaches said incomplete portion of the cylinder and having its edge nearest the cylinder away 35 from the strap as the grazing point reaches the cylinder again, whereby the next fluid forced against the underside of the valve wedges the valve away from the strap, and stops limiting the travel of the valve in each direction.
- 30 6. A pump comprising a casing having intake and discharge chambers and a cylinder, a drive shaft in the cylinder, an eccentric on the drive shaft, a strap on the eccentric, the strap having a close fit within the cylinder 35 whereby rotation of the shaft causes the strap to force fluid ahead of the strap and to draw fluid in behind the strap, the cylinder having an opening, a seal between intake and discharge chambers, and an oscillating check 40 valve mounted coaxially with the rocker and forced against the strap by pressure of fluid in the discharge chamber when the grazing point of strap against cylinder reaches the incomplete portion of the cylinder.
- 45 6. A pump comprising a casing having intake and discharge chambers and a cylinder, a drive shaft in the cylinder, an eccentric on the drive shaft, a strap on the eccentric, the strap having a close fit within the cylinder 50 whereby rotation of the shaft causes the strap to force fluid ahead of the strap and to draw fluid in behind the strap, the cylinder having an opening, a rocker mounted in the casing, a link connecting the rocker and strap and 55 serving as a seal between the intake and discharge chambers, a check valve forced against the strap by pressure of fluid in the discharge chamber when the grazing point of strap

against cylinder reaches the incomplete portion of the cylinder, the valve fitting the contour of the strap as the grazing point reaches said incomplete portion of the cylinder and having its edge nearest the cylinder away from the strap as the grazing point reaches the cylinder again, whereby the next fluid forced against the underside of the valve wedges the valve away from the strap, and a stop limiting the travel of the valve in a direction toward the strap.

7. A pump comprising a casing having intake and discharge chambers and a cylinder, a drive shaft in the cylinder, an eccentric on the drive shaft, a strap on the eccentric, the strap having a close fit within the cylinder whereby rotation of the shaft causes the strap to force fluid ahead of the strap and to draw fluid in behind the strap, the cylinder having an opening, a rocker mounted in the casing a link connecting the rocker and strap and serving as a seal between the intake and discharge chambers, a check valve forced against the strap by pressure of fluid in the discharge chamber when the grazing point of strap against cylinder reaches the incomplete portion of the cylinder, the valve fitting the contour of the strap as the grazing point reaches said incomplete portion of the cylinder and having its edge nearest the cylinder away 80 from the strap as the grazing point reaches the cylinder again, whereby the next fluid forced against the underside of the valve wedges the valve away from the strap, and stops limiting the travel of the valve in each direction.

8. A pump comprising a casing having intake and discharge chambers and a cylinder, a drive shaft in the cylinder, an eccentric on the drive shaft, a strap on the eccentric, the strap having a close fit within the cylinder whereby rotation of the shaft causes the strap to force fluid ahead of the strap and to draw fluid in behind the strap, the cylinder having an opening, a seal between intake and discharge chambers, and a check valve forced against the strap by pressure of fluid in the discharge chamber when the grazing point of strap against cylinder reaches the incomplete portion of the cylinder, the valve fitting the contour of the strap as the grazing point reaches said incomplete portion of the cylinder, and a stop limiting the travel of the valve.

In testimony whereof, I have signed my name to this specification this 24th day of May, 1924.

SHERWOOD HINDS,
